UNITED STATES PATENT OFFICE.

FRANCIS H. KULKA, OF KANSAS CITY, MISSOURI.

LAMP SHADE.

Application filed January 21, 1925. Serial No. 3,755.

This invention relates to lamp shades and more particularly to shades constructed of silk, parchment or the like, stretched upon a wire frame to give the same pleasing form and dimensions. Shades of this character are usually round or oval and oftentimes tapered from the top toward the bottom.

It is the object of this invention to provide suitable means for associating photographic transparencies with these shades which will at the same time maintain the transparency in a curve corresponding to the curve of that portion of the lamp shade.

A further object of the invention is to provide a translucent light diffusing member which is equal in size to the transparency and is placed beneath said transparency and the source of light over which the shade is adapted to be placed.

With these broad general objects in view, the invention will now be described by reference to the accompanying drawing in which,

Figure 1 is a perspective view of a lamp shade embodying this invention.

Fig. 2 is a vertical cross section of a portion of the lamp shade and taken through the photographic transparency on line II-II of Figure 1.

Fig. 3 is a modified form of the way in which the photographic transparency may be applied to a lamp shade.

Fig. 4 is a stretch-out perspective view of the several parts of this invention and showing the lamp shade in a fragmentary way.

Fig. 5 shows a modified form of a transparency which may be applied to the lamp shade.

Fig. 6 is an enlarged detailed section of the frame inter-clamping means.

Fig. 7 is a face view of the same showing the way the spur shaped clamps may be pressed from one of same frame members, and

Fig. 8 is a horizontal section of the photographic transparency taken on line VIII-VIII of Fig. 5 and showing in particular the way all members conform to the general curvature of the lamp shade.

With reference at this time to the drawings in detail wherein similar reference characters refer to like parts throughout the several views and wherein 9 is the ordinary lamp equipped with the well known shade

which is constructed by utilizing a wire frame 10 which is covered with any desired

material such as parchment, silk or other cloth 11.

This shade need not be especially constructed for use with the photographic transparencies forming a part of this invention, but may be stretched with any degree of curvature over frame 10. These photographic transparencies are preferably made upon a pliable material 12 which is slightly larger in size than the opening 13, cut into material 11 when the transparencies are being applied to the shade. A translucent pliable sheet 14 is preferably, though not necessarily, placed in juxtaposition with transparency 12 and between said transparency and the illuminating means of the light not here shown.

Numerous ways of securing transparencies 12 and sheet 14 may be devised for securing the same over opening 13. These transparencies and openings may also be made in any desired shape and the same placed in any position or location over the surface of the lamp shade walls. For the purpose of illustration, the preferable way of mounting transparencies 12 and sheet 14 is shown to be a frame of metal or some other suitable material made up of a front frame 15 and a rear frame 16. The openings in frames 15 and 16 are slightly smaller than the opening 13 in shade 11 and slightly larger than the outside dimension of transparency 12 and sheet 14. Rear frame 16 may or may not be off-set as shown in the drawings, and the method of securing the two together may be varied. This method is shown here to be a series of spurs 18 stamped out of front frame 15 and adapted to pass rearwardly through material 11 and thence through openings 19 registering therewith and formed in rear frame 16. This structure binds material 11 around the edges of opening 13 and precludes any fraying, tearing or running of the fabric. As shown in Fig. 3, the transparency and translucent sheet 14 may be glued directly together with fabric 11 between the same. To remove the unfinished appearance when this method is employed, any suitable binding such as a metallic frame or metallic lace 20, may be secured around the outer edges of transparency 12 as shown.

It is a recognized fact that transparencies will present a completely black surface when no light is placed behind them. If this feature is undesirable, the shade may be con-

structed with a covering of voile 21 stretched over the transparency and frame only, or may be bound to the frame as is the material 11 to form a complete outer covering over 5 the entire shade which conceals to a large extent the transparencies when the light is not lit.

As is shown in Fig. 8, the frames are formed to conform to the curvature of that 10 particular portion of the shade to which the transparency is to be applied. The transparency being pliable, will be held securely with its face conforming to the curvature of said shade.

15 It is understood that many changes and modifications may be made in this invention, and it is desired not to be limited in its construction except as defined in the appended claims.

20 What I claim is:

1. In a lamp shade of the class described, having walls of cloth or the like, said walls having openings cut therein, photographic transparencies positioned over said openings, 25 a translucent sheet of a size equal to said transparencies in juxtaposition thereto and common means for holding said transparencies and translucent sheets over said openings and conforming the same to the general 30 contour of said shade comprising a front and a rear frame adapted to interlock and engage said cloth walls therebetween.

2. In a lamp shade of the class described, having a frame, cloth or the like stretched 35 over said frame to form walls, said walls being provided with openings, said openings each having a photographic transparency thereover, a translucent sheet behind said transparency, and an inner and an outer 40 frame conforming to the shape of said opening adapted to retain said transparency and said translucent sheet therebetween in position and in a position conforming to the general contour of said shade.

45 3. In a lamp shade of the class described, having a frame, cloth or the like stretched over said frame to form walls, said walls being provided with openings, said openings having a photographic transparency registering 50 therewith, and an inner and an outer frame for retaining said transparency in the registered position, both of said frames being curved to correspond to the general curvature of said shade at said opening

whereby the said transparency is held in a 55 curved position corresponding to said shade.

4. In a lamp shade of the class described, having a frame, cloth or the like stretched over said frame to form walls, said walls being provided with openings, a pliable photographic transparency registering with each 60 of said openings, and means for retaining said transparency in the registered position comprising a pair of frames, means integral with one of said frames for piercing said cloth and engaging the other of said frames, whereby said transparency is given a curvature 65 corresponding to said shade, and said cloth or the like is retained in its normal position around said transparency.

5. In a lamp shade of the class described, having a frame, cloth or the like stretched over said frame to form walls, said walls being provided with openings, a pliable photographic transparency registering with 70 each of said openings, and means including a pair of registering metallic frames for holding said transparency in place, said frames having a curvature corresponding to the curvature of said shade at said opening for maintaining the transparency in the same degree of curvature as said shade.

6. In a lamp shade of the class described, having a frame, cloth or the like stretched over said frame to form walls, said walls being provided with openings, a pliable photographic transparency registering with 75 each of said openings, and means for securing said transparency to said walls, said means being adapted to protect the material in said walls from fraying or running at the edges formed by the cutting of said opening.

7. In a lamp shade of the class described, having a frame, cloth or the like stretched 80 over said frame to form walls, said walls being provided with openings, a pliable photographic transparency registering with each of said openings, a frame supporting 85 said transparency and gripping said walls at the edge of said opening and an outer covering forming a part of said lamp shade stretched over said transparencies whereby 90 the same are concealed when said lamp shade is not illuminated from the inner side.

In testimony whereof I hereunto affix my signature this 17th day of January, 1925.

FRANCIS H. KULKA.
